(57) **CLAIM**

The ornamental design for an outdoor unit for air conditioner as shown and described.

DESCRIPTION

FIG. 1 is a front, top, right side perspective view of an outdoor unit for air conditioner showing our new design; FIG. 2 is a rear, top, left side perspective view thereof; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

The broken lines in the drawings are for the purpose of illustrating portions of the outdoor unit for air conditioner that form no part of the claimed design.

1 Claim, 8 Drawing Sheets
